COMBINED PIPE RACK AND STORAGE CONTAINER

Brette R. Riley, Pratt, Kans., assignor to Divisible Packaging Enterprises, Inc., Pratt, Kans., a corporation of Kansas

Filed May 12, 1969, Ser. No. 17,112

Term of patent 14 years

Int. Cl. D27—02

U.S. Cl. D85—8

Fig. 1.

Fig. 2.

Fig. 3.

Fig. 4.

Fig. 5.

FIG. 1 is a front perspective view of a combined pipe rack and storage container embodying my new design;

FIG. 2 is a view looking from the left of FIG. 1 with the handle supporting the combined pipe rack and storage container in a tilted position;

FIG. 3 is a front elevational view;

FIG. 4 is a rear elevational view; and

FIG. 5 is a top plan view thereof.

I claim:

The ornamental design for a combined pipe rack and storage container, as shown.
